UNITED STATES PATENT OFFICE

JOHN FRANKLIN PATTERSON, OF WARREN, OHIO, ASSIGNOR TO THE WARREN CITY TANK & BOILER COMPANY, OF WARREN, OHIO, A CORPORATION OF OHIO

WATER ROOF TANK

Application filed October 8, 1927. Serial No. 224,956.

This invention aims to provide novel means whereby the top of an oil tank or other tank may bow upwardly to a predetermined extent, under an internal pressure, novel means being provided for opening a valve when the top of the tank has bowed up to a predetermined degree.

It is within the province of the disclosure to improve generally and to enhance the utility of devices of that type to which the invention appertains.

With the above and other objects in view which will appear as the description proceeds, the invention resides in the combination and arrangement of parts and in the details of construction hereinafter described and claimed, it being understood that changes in the precise embodiment of the invention herein disclosed, may be made within the scope 20 of what is claimed, without departing from the spirit of the invention.

In the drawings:—

Figure 1 shows in top plan, a tank equipped with the device forming the subject matter of 25 this application;

Figure 2 is a section on the line 2—2 of Figure 1, the top of the tank being in a normal position.

Figure 3 is a detail enlarged from Figure 2;

Figure 4 is a fragmental transverse section on the line 4—4 of Figure 3;

Figure 5 is a sectional view with the top or loop of the tank bowed up to a maximum 35 amount, the valve being about to open.

The numeral 1 marks the wall of an oil tank, or other tank, within which is disposed a frame work 2, which may be channel members, as shown in Figure 4, the frame work 40 2 supporting, ordinarily, the roof 3 of the tank, the roof 3 having a rim 5 which is secured at 4 to the wall 1 of the tank, the roof having an easy curve, as shown at 6, where the body of the roof joins the rim, the construction being such that the roof 3 may bow up, under internal pressure within the tank, from the position shown in Figure 3 to the position shown in Figure 5, although Figure 5 is more or less diagrammatic as to the actual 50 position of the roof when it bows up. The

rim 5 of the roof 3, and the upper edge of the wall 1 of the tank, form a basin in which water often is placed, to avoid fire and for other purposes. The numeral 7 designates a flexible metal pipe located below the roof 3 and supported at 8 on the roof, in brackets. The inlet end of the pipe 7 is marked by the numeral 9, and extends upwardly through the roof 3, to regulate the depth of the water on the roof. The outlet end 10 of the flexible 55 pipe 7 is extended through the side wall 1 of the tank and is down-turned, as shown in Figures 3 and 5 of the drawings. Owing to the fact that the pipe 7 is flexible, the roof 3 of the tank may bow upwardly under pressure, without breaking the pipe. 60

A two-part fulcrum bracket 11 is connected at its upper end to the frame work 2, the lower end of the bracket 11 being laterally and downwardly inclined, as shown at 12 in 70 Figures 3 and 5 of the drawings. The bracket 11 is sustained by an inclined brace 14 secured to the bracket and to the frame work 12. A lever 15 extends between the constituent members of the bracket 11. The lever 15 is fulcrumed as shown at 16, intermediate its ends, on the bracket 11. A weight 17 is adjustably secured, as at 18, to the outer end of the lever 15. The inner end of the lever 15 is pivoted at 19 to a link 20, which, in its turn, is pivoted 75 at 21 to a connection or stem 22, in the form of a rod, the connection 22 being slidable in a guide spider 23 secured in a tubular member 24 attached to the roof 3 about an opening 25 in the roof. A platform 26 is secured 80 to the upper end of the tubular member 24, and the platform 26 has an opening 27 across which extends a plate 28 provided with a valve seat 29. A valve 30 cooperates with the seat 29, the valve being an upwardly 85 closing valve. The valve 30 is threaded for adjustment on the connecting rod 22 and is held in adjusted positions by means of a nut 31 threaded on the upper end of the rod 22 and bearing against the valve. The valve 30 and attendant parts are housed beneath a hemi-spherical cap 32 which is connected by a perforated web 33 with the plate 28. 90

In practical operation, the valve 30 may be 95 adjusted along the connection 22 and may be 100

held in adjusted position by means of a nut 31, so that when the roof 3 has bowed up under pressure, to a predetermined point, the valve 30 will open, if the roof bows beyond that point. As the roof 3 rises, the link 20 moves into alignment with the connection or rod 22, and the lever 15 tilts on its fulcrum 16 until the lever strikes against the end of the part 12 of the bracket 11 at the place where the numeral 34 is applied in Figure 4 of the drawings. Thereafter, the lever 15 will tilt no further, and as the roof 3 bows upwardly, carrying with it the seat 29, the seat will be opened with respect to the valve 30, and the pressure within the tank will escape through the seat 29 into the cap 32 and out through the perforated web 33.

The invention embodies, among other combinations, a tank having a flexible roof 3; a closure mechanism comprising as cooperating parts, a valve 30 and a valve seat 29; means for mounting one of said cooperating parts, for instance the seat 29, on the roof, and means for mounting the other of said cooperating parts, for instance the valve 30, in such position that when the roof 3 flexes, one of said cooperating parts, for example, the seat 29, will be moved relatively to the other of said cooperating parts, for example the valve 30, thereby to open the aforesaid closure mechanism and bring about a venting of the tank.

Although the seat 29 is claimed as being carried by the roof 3, and the valve 30 by the stem 22, this is not to be construed as meaning that I am not entitled to the use of an equivalent construction.

What is claimed is:—

1. In a device of the class described, a tank having a flexible roof, a tubular member mounted on the roof, a valve seat carried by the tubular member, a spider mounted in the tubular member, a connecting rod slidable in the spider, a valve which closes against the under side of the seat, means for mounting the valve on the connecting rod for adjustment longitudinally of the connecting rod, a frame work within the tank, a fulcrum bracket mounted on the frame work and having an inclined end, a lever pivotally mounted intermediate its ends on the bracket, a link pivoted to one end of the lever and to the connecting rod, a weight adjustable along the opposite end of the lever, means for holding the weight in adjusted positions along the last-specified end of the lever, and the last-specified end of the lever being engageable with the inclined end of the fulcrum bracket after the lever has tilted a predetermined amount, thereby to stop the movement of the lever and the valve and to permit the seat to move with the roof, away from the valve, when the roof flexes beyond a predetermined point, thus bringing about a venting of the tank through the seat.

2. In a storage device for oil and like substances capable of creating a gas pressure, a tank having an upwardly-flexible roof provided with a valve seat, a valve cooperating with the seat, continuously-acting mechanism carrying the valve, and adjustably under the control of an operator, for holding the valve yieldably closed whilst the roof is bowed downwardly, and whilst the roof is bowing upwardly to a predetermined point, 75 said mechanism being supported movably on the tank, independently of the roof, said mechanism embodying a member which is actuated by the engagement between the valve and the seat, as the roof bows upwardly with the valve in closed position, and means carried by the tank, independently of the roof, and engaging said member to stop the movement of said mechanism after the roof has bowed upwardly to said predetermined point, 80 whereby upon further upward bowing of the roof, the seat will be raised with respect to the valve and bring about a venting of the tank.

3. In a storage device for oil and like substances capable of creating a gas pressure, a tank having an upwardly-flexible roof provided with a valve seat, a valve cooperating with the seat, a substantially horizontal lever, means for fulcruming the lever intermediate 85 its ends on the tank, independently of the roof, a weight adjustable longitudinally of one end of the lever, means for holding the weight in adjusted positions longitudinally of said end of the lever, a stem on which the valve is mounted, a link pivoted to the stem and to the opposite end of the lever, and means supported by the tank, independently of the roof, and engaging the lever, to stop the movement of the lever after the lever has 105 been swung a predetermined amount by the engagement between the valve and the seat (as the roof bows upwardly with the valve in closed position) thereby to bring about a venting of the tank, the weight being adjustable, as aforesaid, at the will of an operator, and acting continuously to hold the valve yieldably closed whilst the roof is bowed downwardly, and whilst the roof is bowing upwardly to point where the last-specified 110 means stops the movement of the lever and brings about a venting of the tank.

In testimony that I claim the foregoing as my own, I have hereto affixed my signature.

JOHN FRANKLIN PATTERSON.
